UNITED STATES PATENT OFFICE.

CARL FISCHER, OF WEST HOMESTEAD, PENNSYLVANIA, ASSIGNOR TO AMERICAN HEAT ECONOMY BUREAU, OF PITTSBURGH, PENNSYLVANIA, A CORPORATION OF DELAWARE.

BURNER.

Application filed March 24, 1927. Serial No. 178,047.

My invention is an improvement in burners and relates more particularly to that class of fuel burners which are especially adapted for use in supplying heat to furnaces, such as open hearth and industrial furnaces, by introducing the nozzle of the burner through an opening in the wall or shell of the furnace to discharge the flame therein.

10 The main object of my invention is to provide a burner of this type in which the fuel in either gaseous, liquid or powdered form is thoroughly mixed with air in a commingling chamber from which it is discharged through a nozzle to produce a concentrated flame, the particular construction of my improved burner effecting a whirling motion of the combustible mixture in the commingling chamber to produce an admixture that

15 will give maximum heat and will result in an economical consumption of the fuel.

A further object of my invention is to provide a fuel burner that is simple and compact in construction, and in which the 20 parts thereof are so constructed and assembled that they can be readily separated for cleaning the same when necessary.

With these principal objects in view my invention consists of a burner for gaseous, 25 liquid and powdered fuel comprising a body portion having a cylindrical commingling chamber with fuel and air passages leading into the same and a discharge opening opposite the fuel passage, said body portion containing a detachable fuel discharging tube extending axially into the cylindrical commingling chamber, and a detachable nozzle for the discharge opening to concentrate the combustible mixture in its discharge from the burner, the commingling chamber having 30 diagonally disposed vanes around the fuel discharging tube to cooperate with tangential fuel discharging openings through said tube to effect a thorough admixture of the fuel and air on its passage through the burner, all as hereinafter fully described and particularly set forth in the appended claims.

35 In the accompanying drawings:

Figure 1 is a side elevation of a fuel burner constructed in accordance with my invention.

Fig. 2 is a vertical transverse sectional view through the same.

Fig. 3 is a vertical sectional view on the 55 line 3—3 of Fig. 2.

Fig. 4 is a detail front view of the detachable nozzle.

Fig. 5 is a detail view of the fuel discharging tube.

Figs. 6 and 7 are sectional views through the fuel discharging tube on the lines 6—6 and 7—7 of Fig. 5.

In carrying out my invention the main portion or body of the burner is formed by 65 casting to provide a cylindrical commingling chamber 10 with a large pipe extension 11 at the periphery thereof, a small pipe extension 12 projecting from the center of the rear wall of said commingling chamber 70 and a circular discharge opening 13 in the front wall opposite the last mentioned pipe extension, an annular flange 14 being formed on the front wall around the discharge opening to receive a funnel-shaped discharge nozzle 15 attached thereto by bolts 16 passing through ears 17 at the enlarged end of said nozzle into the flange on the body portion of the burner. The pipe extension 11 is for supplying air to the commingling 75 chamber and the fuel is fed into the same through the pipe extension 12, said pipe extensions being threaded at their outer ends for the connection of pipes leading from the air and fuel supply.

80 Threaded into the inner end of the pipe extension 12, to extend across the center of the commingling chamber there is a fuel discharging tube 18 of such length that its outer closed end 18^a extends slightly beyond 85 the discharge opening 13, said fuel discharging tube having narrow longitudinal openings or slits 19 through the sides thereof tangentially for discharging the fuel into the commingling chamber in such manner as to 90 cooperate with diagonally disposed vanes 20 extending across the commingling chamber and arranged in series around the fuel discharging tube. The annular series of vanes or baffle-plates 20 are located beyond the 95 plane of the circular discharge opening 13 leaving an annular space around the same within the peripheral wall of the commingling chamber, as well as an annular space 100 between said baffle-plates and fuel discharging tube, and it will be noted that the tangential openings or slits in the fuel discharging tube do not extend the full width of the 105

commingling chamber but are in the forward portion thereof to permit uninterrupted currents of air to flow around the rear portion of said commingling chamber 5 and commingle with the currents of air into which the fuel is discharged, the tangential discharge openings 19 cooperating with the baffle-plates 20 to impart a whirling motion to the admixture of fuel and air which is 10 maintained as the combustible mixture passes through and out of the discharge-nozzle 15, whereby the fuel and air are further commingled and the flame from the burner is concentrated and has a swirling 15 action that will increase the intensity of the heat.

The air inlet 11 is provided with a valve or damper 21 for regulating the amount of air fed to the commingling chamber, the stem 20 21^a of the valve having an operating lever 22 on its outer end with a pointer 22^a moving over a dial-plate 23, and in like manner the fuel inlet 12 is provided with a similar valve (not shown) operated by lever 24 also 25 provided with a pointer, 24^a, moving over dial-plate 25, these valves providing for accurately proportioning the fuel and air admitted to the commingling chamber. Any 30 form of valve and cooperating regulating means may be employed for the purpose mentioned, the arrangement shown being a conventional type of regulating valve, it being understood however that the provision of proportioning valves increase the effectiveness of the burner.

In the operation of the burner either gaseous, liquid or powdered fuel may be used being fed into the commingling chamber through the discharge openings or slits 19 in 40 the tube 18 connected to the valved inlet pipe 12, and as the fuel is discharged into the commingling chamber tangentially the air which enters from the valved inlet pipe 11 takes it up and a rapid whirling motion is 45 imparted to the admixture by the diagonally disposed baffle-plates 20 to thoroughly mix the same together in the commingling chamber and as they pass through and out of the nozzle 15, the valves being properly adjusted 50 to proportion the fuel and air according to the fuel used and the character of flame desired. Any fuel or combination of fuels, liquid, gaseous or powdered, may be employed, the arrangement of the inlet openings 11 and 12 with respect to the cylindrical commingling chamber in connection 55 with the special form of feeding tube 18 and cooperating baffle-plates providing for a thorough admixture of the combustible mixture in its passage from the commingling chamber and through the tapered discharge nozzle; in other words, the several elements of the burner cooperate in an effective manner to produce a flame of intense heat.

60 The burner may be used for various pur-

poses, and is particularly adapted for supplying heat to furnaces of all kinds as it provides an intense heat from a concentrated flame that can be directed to any point desired and the thorough admixture of the 65 fuel and air effects an economy in the consumption of the fuel.

When the burner needs cleaning the nozzle and fuel discharging tube can be readily disconnected and removed from the body 70 portion for the purpose, and in re-assembling the parts the fuel discharging tube is adjusted so that the discharge-openings therein will direct the fuel as desired with respect to the baffle-plates, as for instance towards 75 the inner end thereof as shown in Fig. 3.

It will be obvious that by the particular construction herein shown and described I produce a burner that can be manufactured and sold at small cost, that it will be durable 80 in use and positive in its action, and that it can be readily adjusted to vary the proportions of the admixture of fuel and air. Furthermore it will be obvious that minor 85 modifications or changes may be made in the formation of the burner parts and yet obtain similar results, all within the spirit and scope of the following claims.

I claim:

1. A burner comprising a body portion 90 having a commingling chamber with fuel and air inlet openings leading into the same at right angles to each other and a discharge opening in one side, a fuel discharging tube leading into the commingling chamber 100 from the fuel inlet openings and having tangential discharge openings, a series of baffle-plates in the commingling chamber surrounding the fuel discharging tube, and a contracted nozzle attached to the body portion to receive the admixture of fuel and air 105 from the discharge opening of the commingling chamber.

2. A burner comprising a body portion 110 having a cylindrical commingling chamber with fuel and air inlet openings leading into the center of a side wall and the periphery of said cylindrical commingling chamber, a fuel discharging tube extending into the commingling chamber axially from 115 the fuel inlet opening and having tangential discharge openings in the sides thereof, and a series of baffle-plates in the commingling chamber surrounding the fuel discharging tube.

3. A burner comprising a body portion 120 having a cylindrical commingling chamber with fuel and air inlet openings leading into the center of a side wall and the periphery thereof respectively, with a discharge opening in the body portion opposite the fuel inlet opening, a fuel discharging tube extending across the commingling chamber axially to the center of the discharge opening, and a series of diagonally 125

disposed baffle-plates surrounding the fuel discharging tube, the latter having tangential openings in the sides thereof for discharging the fuel against the baffle-plates.

5. 4. A burner comprising a body portion having a cylindrical commingling chamber with fuel and air inlet openings leading into the center of a side wall and the periphery thereof respectively with a discharge opening in the wall opposite the fuel inlet opening, a fuel discharging tube extending across the commingling chamber axially to the center of the discharge opening and having tangential openings in the sides thereof 10 through which the fuel is discharged, a series of diagonally disposed baffle-plates surrounding the fuel discharging tube, and a nozzle receiving the admixture from the discharge opening of the commingling chamber, said nozzle being contracted to its outer end.

5. A burner comprising a body portion having a cylindrical commingling chamber with a pipe extension from the periphery thereof through which air is supplied, a pipe extension projecting from the center of one side of said commingling chamber through which the fuel is supplied, a discharge opening in the opposite side of the commingling chamber from the fuel supply, and an annular series of transverse baffle-plates extending around the inner side of the commingling chamber beyond the plane 30 of the discharge opening; together with a

detachable fuel discharging tube threaded 35 into the inner end of the fuel supply opening to project axially across the center of the commingling chamber into the center of the discharge opening and having tangential openings in the sides thereof to discharge 40 the fuel towards the baffle-plates, and a tapered nozzle detachably connected to the body portion of the burner to receive the fuel mixture from the aforesaid discharge opening of the commingling chamber. 45

6. A burner comprising a body portion having a cylindrical commingling chamber with a valved pipe extension from the periphery thereof through which air is supplied, a valved pipe extension projecting 50 from the center of one side of said commingling chamber through which fuel is supplied, a discharge opening in the opposite side of the commingling chamber from the fuel supply, and an annular series of transverse 55 baffle-plates extending around the inner side of the commingling chamber; together with a fuel discharging tube extending from the fuel supply opening into the commingling chamber axially and having tangential discharge opening in the sides thereof cooperating with the baffle-plates, and a nozzle secured to the body portion of the burner to receive the fuel mixture from the discharge opening of the 60 commingling chamber. 65

CARL FISCHER.
